UNITED STATES PATENT OFFICE.

LULU VERHAREN LAVELL, OF MINNEAPOLIS, MINNESOTA.

DESIGN FOR A CURTAIN HOLDBACK.

Application filed March 23, 1928. Serial No. 25,962. Term of patent 3½ years.

To all whom it may concern:

Be it known that I, LULU VERHAREN LAVELL, a citizen of the United States, residing at 3524 Dupont Avenue south, in Minneapolis, in the county of Hennepin and State of Minnesota, have invented a new, original, and ornamental Design for Curtain Holdbacks, of which the following is a specification, reference being had to the accompanying drawing, forming part thereof.

The figure is a perspective view of a curtain holdback, showing my new design.

I claim:

The ornamental design for a curtain holdback, as shown.

LULU VERHAREN LAVELL.
